LIONEL WOLFFSOHN, (NOW BY JUDICIAL CHANGE OF NAME LIONEL M. WOOLSON,) OF HOBOKEN, NEW JERSEY, ASSIGNOR, BY MESNE ASSIGNMENTS, TO BIJUR MOTOR APPLIANCE COMPANY, A CORPORATION OF DELAWARE.

ENGINE-STARTING APPARATUS.

1,330,566.

Specification of Letters Patent. Patented Feb. 10, 1920.

Application filed February 29, 1916. Serial No. 81,083.

To all whom it may concern:

Be it known that I, LIONEL WOLFFSOHN, a citizen of the United States, and a resident of Hoboken, in the county of Hudson and State of New Jersey, have invented an Improvement in Engine-Starting Apparatus, of which the following is a specification.

This invention relates to engine starters and more particularly to motor driven apparatus for starting internal combustion engines. One of the objects thereof is to provide simple and practical apparatus for starting engines especially adapted for use with engines of the internal combustion type. Another object is to provide apparatus of the above type of compact and inexpensive construction and efficient action. Another object is to provide apparatus of the above nature in which the requisite movement of parts for bringing the source of starting power into mechanical connection with the engine is reduced to a minimum. Other objects will be in part obvious and in part pointed out hereinafter.

The invention accordingly consists in the features of construction, combinations of elements and arrangement of parts which will be exemplified in the structure hereinafter described and the scope of the application of which will be indicated in the following claims.

The accompanying drawing is a diagrammatic sectional elevation of one of various possible embodiments.

Referring now to this drawing in detail, there is indicated at 1 an internal combustion engine on the crank shaft 2 of which is mounted a fly wheel 3. This fly wheel has formed or secured about its surface a pair of gear portions 4 and 5 relatively spaced one from another.

Mounted with its shaft 6 substantially parallel to the crank shaft 2 is an electric motor 7 provided with an outer casing 8, a stator in the form of field magnets 9, a rotor preferably in the form of an armature 10 and other usual parts required to make up an operative source of power. The armature shaft 6 is mounted in suitably lubricated bearings 11 and 12 for both rotary and sliding movement. This shaft, together with the armature 10, commutator 13 and other parts connected therewith, normally occupies the position indicated in dotted lines

at the extreme of its movement toward the left, and is yieldingly held in such position by a spiral spring 14. This spring is compressed between a collar 15 on the armature and an annular cup 16 mounted freely on the motor head by means of a ball bearing 17. The commutator 13 is of such length as to permit a considerable range of sliding movement without going out of operative relation to the brushes 18.

At the left-hand end of the dynamo casing is mounted a switch casing 19 provided with switch mechanism 20. This switch is controlled by the movement of a member 21 on the end of shaft 6 as the armature shaft slides as hereinafter described. Although the details of this mechanism are not shown as it forms in itself no part of the present invention, it may be noted that the switch is so formed and connected that the sliding movement of the armature shaft acts automatically to increase the effective current supplied to the motor.

At the opposite end of the shaft 6 there is keyed thereon and held in position by the nut 22 a gear 23. This gear is provided with a pair of toothed portions 24 and 25 mating in width, pitch and alignment with the teeth of the gear portions 4 and 5 on the fly wheel. Normally the several gear portions are relatively offset and out of mesh as indicated by the dotted lines showing the position occupied by the gears 24 and 25. With the parts in this position and understanding that the gears or gear portions 4 and 5, as well as the gears or gear portions 24 and 25, are separated in each case by an intermediate groove, the gear 4 will be opposite the groove between gears 24 and 25 and the gear 25 will be opposite or rest in the groove between the gears 4 and 5. Also the armature as shown will be offset from registering position with the field magnets. If, however, current be led to the motor, the magnetic pull of the field magnets on the armature draws the latter with the parts connected therewith toward the right into the position indicated in full lines in the drawing. This sliding movement throws the gear portions 24 and 25 respectively into mesh with the gear portions 4 and 5 and this effects a power-transmitting connection between the motor and the engine.

In this manner there are formed two

power-transmitting devices connecting the motor and engine, namely that formed by gears 4 and 24 and that formed by gears 5 and 25. The rotary movement of the motor thereupon turns over the engine and cranks the same. When the engine assumes its regular cycle of operations, the current may be cut off from the motor, thus permitting the spring 14 to return the parts to their 10 normal offset position. The engine is then running and the motor disconnected therefrom.

It is to be especially noted that for a given strength of mechanical connection between 15 the engine and the motor in the above action, there is required a relatively short movement of translation of the armature shaft and connected parts. If for example, it is desired that the gearing in mesh be one inch 20 in width, with ordinary gears a movement of one inch plus a suitable slight clearance would be required. In the present case, however, for the same strength of connection, the two gear portions may each be one-half 25 inch in width and a total movement of only a little more than one-half inch is required. This saving in movement not only reduces wear and attains other advantages in action, but is of extreme importance in crowded 30 relations such as those in which apparatus of this nature is mounted in automobiles. The total or overall length of the starting motor with its attached parts is increased with a sliding armature construction by an amount 35 which is double the range of travel of the sliding movement. In the first place, the commutator, to accommodate the brushes, must be elongated by an amount equal to the sliding movement and furthermore, the 40 motor must be elongated by an amount equal to the sliding movement to accommodate the travel of the commutator and other parts. If then the range of travel is cut down from say one and one-half inches to three quarters 45 of an inch, the saving in total length is not merely three quarters of an inch, but is this amount doubled, or one and one-half inches.

It will thus be clear that there is provided apparatus which not only is highly efficient 50 in action and of inexpensive construction, but in which very material compactness is attained without sacrifice of these qualities.

As various possible embodiments might be made of the above invention and as various changes might be made in the embodiment above set forth, it is to be understood that all matter herein set forth or shown in the accompanying drawing is to be interpreted as illustrative and not in a limiting 60 sense.

I claim as my invention:

1. In apparatus of the class described, in combination, an internal combustion engine, an electric motor, said motor comprising an 65 armature yieldingly held in offset relation

to the field magnets of said motor, and a plurality of power-transmitting devices, one portion of each of which is connected with the shaft of said armature, and the other portion of each of which is connected with 70 said engine, said first portions being mounted to simultaneously enter into operative relation with the engine portions of said devices as the field magnets of said motor tend to draw the armature thereof toward register- 75 ing position.

2. In apparatus of the class described, in combination, an internal combustion engine provided with a fly wheel, a pair of gears about said fly wheel laterally offset from 80 one another, a pair of gears laterally offset one from another and normally laterally offset from the gears of said fly wheel, and means adapted to move the gears of said second pair in an axial direction substantially simultaneously into mesh with the gears of said first pair, and to then transmit cranking torque through said gears to said engine.

3. In apparatus of the class described, in combination, an internal combustion engine provided with a fly wheel, a pair of relatively spaced gears about said fly wheel, a motor provided with an axially slideable armature normally offset from its field magnets, a spring tending to hold said armature in said position, and a power-transmitting member fixed upon the shaft of said motor and provided with a pair of gears normally offset from the gears of said fly wheel with 90 one gear of each pair opposite the space between the gears of the other pair, said gears being positioned to slide relatively into mesh as the field magnets of said motor are energized to draw its armature toward register- 95 ing position.

4. Apparatus of the class described, comprising in combination, an internal combustion engine, having a driven member connected therewith, a motor having rotor and stator elements, a driving member connected to one of said elements, normally out of engagement with said driven member and mounted for displacement with respect to one of said motor elements characterized 110 by the fact that said driving and driven elements are constructed and arranged so that said motion of displacement causes positive driving engagement between said members along a width greater than the amount of 115 said displacement.

5. Apparatus of the class described, comprising in combination, an internal combustion engine, an electric motor, said motor comprising an armature yieldingly held in 120 offset relation to the field magnets of said motor, a power transmitting connection between said machines including gear teeth constructed and arranged to cause a meshing thereof responsive to the displacement of 125 130

said armature in being drawn into registry with said field magnets along a length greater than and in the direction of said displacement.

- 5 6. Apparatus of the class described, comprising in combination, an internal combustion engine, an electric motor, said motor comprising an armature yieldingly held in offset relation to the field magnets of said
10 motor, a driven member connected to said engine, a driving member connected to said armature, and normally out of engagement

with said driven member, said driving and said driven member being each provided with a plurality of engaging surfaces of 15 substantially uniform width adapted to be substantially simultaneously engaged, to divide the cranking torque substantially equally between the plurality of coöperating pairs of surfaces.

In testimony whereof, I have signed my name to this specification this 24th day of February, 1916.

LIONEL WOLFFSOHN.
